UNITED STATES PATENT OFFICE.

DAVID DUNLAP LOW, OF NITTAYUMA, MISSISSIPPI.

DESIGN FOR A BALE-TIE BUCKLE.

SPECIFICATION forming part of Design No. 32,564, dated April 24, 1900.

Application filed March 27, 1900. Serial No. 10,096. Term of patent 14 years.

To all whom it may concern:

Be it known that I, DAVID DUNLAP LOW, a citizen of the United States, residing at Nittayuma, in the county of Sharkey and State 5 of Mississippi, have invented and produced a new and original Design for a Bale-Tie Buckle, of which the following is a specification.

This invention relates to a new and original o design for a bale-tie buckle; and it has for its object to provide a design of this character that shall be both useful and ornamental.

The leading feature of the design resides in the approximately-rectangular plate provided 5 in diametrically-opposite edges thereof with reversely-inclined J-shaped notches, said plate being further provided in the body portion thereof with a pair of spaced holes.

The minor features of the design are the o plate having the longer side or wall of each notch extending to one corner of the plate and the hooked or curved wall of each notch disposed at a point intermediate the ends of the plate.

5 In the drawings, Figure 1 is a perspective view of a bale-tie buckle embodying the here-

in-described design. Fig. 2 is a plan view thereof.

Referring to the accompanying drawings, the numeral 1 designates the body-plate of the buckle, which is of an approximately-rectangular contour and is provided in diametrically-opposite edges thereof with the opposite reversely-inclined J-shaped notches 2. The longer side or wall of each notch extends 35 to one corner of the plate and the hooked or curved wall of the notch is disposed at a point intermediate the ends of the plate.

To complete the design, the plate 1 is provided within the body portion thereof and 40 centrally between the oppositely-located notches 2 with a pair of spaced circular holes 3.

What is claimed is—

The design for a bale-tie buckle herein shown and described.

In testimony that I claim the foregoing as my own I have hereto affixed my signature in the presence of two witnesses.
